[57] CLAIM

The ornamental design for a kitchen utensil holder, as shown and described.

DESCRIPTION

FIG. 1 is a front elevational view of a kitchen utensil holder showing my new design.

FIG. 2 is a side elevational view thereof viewed from line 2—2 on FIG. 1.

FIG. 3 is a side elevational view thereof viewed from line 3—3 on FIG. 1.

FIG. 4 is a rear elevational view thereof;

FIG. 5 is a top plan view thereof viewed from line 5—5 on FIG. 1.

FIG. 6 is a bottom plan view thereof viewed from line 6—6 on FIG. 1.

FIG. 7 is a front elevational view similar to FIG. 1, the broken line showing of a spoon and spatula being for the purpose of illustrating environmental use only.

FIG. 2FIG. 1FIG. 3FIG. 4FIG. 5FIG. 6FIG. 7
